PREPARATION OF DINITROTOLUENE AND TRI-NITROTOLUENE WITH BORON TRIFLUORIDE AND NITRIC ACID

Jean P. Picard, Morristown, Daniel R. Satriana, Verona, and Louis Silberman, Dover, N.J., assignors to the United States of America as represented by the Secretary of the Army

No Drawing. Filed Feb. 8, 1966, Ser. No. 526,335
8 Claims. (Cl. 260—645)

The invention described herein may be manufactured and used by or for the Government for governmental purposes without the payment to us of any royalty thereon.

This invention relates to explosives and more particularly concerns improved processes for the manufacture of trinitrotoluene and dinitrotoluene.

At present, 2,4,6-trinitrotoluene (hereinafter referred to as TNT) explosives are generally manufactured by a 3-stage process wherein toluene is reacted with a mixture of nitric and sulfuric acids. The toluene is nitrated in a stepwise manner to TNT as follows:

The quantity of H_2SO_4 required for the manufacture of TNT by the above process is large. TNT is a high explosive, relatively insensitive to shock and fulfills vital military as well as industrial needs. To counteract the possibility of shortages of this acid in times of emergency, various unsuccessful attempts have been made to eliminate the necessity of using H_2SO_4 in the manufacture of TNT.

It is therefore a broad object of this invention to provide methods of manufacturing TNT wherein the use of H_2SO_4 is not required.

Another object of this invention is to provide methods for the manufacture of TNT wherein a 1-step nitration process only is required.

Still another object of this invention is to provide methods to efficiently convert toluene to DNT by spent acid formed in our 1-step nitration process above mentioned.

Other objects and advantages of the invention will be obvious or appear hereinafter in the following detailed description.

Briefly, we have discovered that toluene and a mixed acid consisting of BF_3 and HNO_3 can be reacted to yield 86.4% of TNT having a purity of about 92.5%.

More specifically, we have discovered that when HNO_3 , having a concentration of 98.6%, and 30 to 60% BF_3 is mixed therewith to form a mixed acid, was reacted with toluene for 30 to 240 minutes and refluxed, that high yields and purities of TNT can readily be produced.

The toluene to nitric acid molar ratio must be in excess of 1 to 3, although molar ratios approximating 1 to 10 are preferred. A minimum reflux time of about 1 hour is required in nitration wherein the BF_3 ranges from between about 30 to 60 weight percent. Excellent yield and purity of TNT may be obtained when the mixed acid concentra-

2

tion is 40 weight percent BF_3 and 60 weight percent HNO_3 (98.6%) and refluxed for about 2 hours. The difference in density between the TNT and spent acid permits a clean separation of the TNT product from the reaction medium.

The reflux temperature will normally be about 90–95°C. and the reaction temperature during the addition of toluene will normally be maintained between about 30–50°C.

10 The spent acid formed in our 1-step nitration process can effectively be used to nitrate toluene to produce DNT in yields approaching 76%. The DNT thus formed can be further nitrated with fresh mixed acid, preferably BF_3/HNO_3 (98.6%) in weight ratio of 40/60 to realize an 83% yield of TNT having a purity of about 80%. The time of reflux for converting DNT with out spent acid is about 5 minutes whereas reflux time for converting DNT to TNT is approximately 2 hours.

15 We have found that a product having slightly better yields and purities are obtained with mixed acids containing by weight percent $40BF_3/60HNO_3$ (98.6%) than $20BF_3/80HNO_3$ (98.6%) and $60BF_3/40HNO_3$ (98.6%). The overall recovery of spent acid ranged from about 50 to 72 weight percent in nitrations that contained BF_3 concentrations of about 40%.

20 Although it is not intended that the invention be limited thereto, there is set forth hereinbelow for purposes of illustration, examples of values which may suitably be employed in practicing our invention, all percentages being 25 weight percentages:

Example I

18 grams (0.195 mole) of toluene were added to 200 grams of mixed acid consisting of 60% BF_3 and 40% HNO_3 (98.6%). During the addition, the mixture was stirred vigorously and temperature maintained between 30°–50° C. by means of a cooling bath. After addition of toluene was completed, the reaction was refluxed (90–95° C.) for one hour, cooled to about 70° C., and transferred 30 to a separatory funnel. The two liquid phases were separated.

35 The upper layer, consisting mainly of trinitrotoluene, was poured into ice water. The product was filtered, washed free of acid and dried. The lower layer (162 g.), 40 consisting of spent acid and some residual product, was also poured into an ice-water mixture. The solid, after filtering, washing and drying, was added to the main portion. The total weight of crude trinitrotoluene was 35.3 g. (79.3% of theoretical) having a purity of 65.6%.

Example II

45 This example is identical with Example I except reflux time was increased to 2 hours. The yield of crude trinitrotoluene was 36.4 g. (81.7% of theoretical) having a purity of 76.2%. The weight of spent acid was 164 grams or 55 82.6% recovery.

Example III

50 This example is identical with Example I except reflux time was increased to 3 hours. The crude yield of tri-nitrotoluene was 36.4 g. (81.7% of theoretical) having a purity of 84.9%. The weight of spent acid was 160 g. of 80.1% recovery.

Example IV

55 18 grams (0.195 mole) of toluene were added to 200 grams of mixed acid consisting of 50% BF_3 and 50% HNO_3 (98.6%). The experimental procedure was identical to that described in Example I. The crude yield of trinitrotoluene (79.5% purity) was 37.1 grams or 83.4% 60 of theoretical. The weight of spent acid was 159 grams or 79.6% recovery.

3
Example V

This example is identical with Example IV except reflux time was increased to 2 hours. The crude yield of trinitrotoluene (89.1% purity) was 36.6 grams or 82.1% of theoretical. The weight of spent acid was 160 grams or 79.8% recovery.

Example VI

This example is identical with Example IV except reflux time was increased to 3 hours. The yield of crude trinitrotoluene (91.4% purity) was 36.8 grams or 82.7% of theoretical. The weight of spent acid was 158 grams (79.0% recovery).

Example VII

18 grams (0.195 mole) of toluene were added to 200 grams of mixed acid consisting of 40% BF_3 and 60% HNO_3 (98.6%). The experimental procedure was similar to that described in Example I. The time of reflux for the reaction was one hour. 37.5 grams (84.2% theoretical) of crude trinitrotoluene (79.2% purity) was obtained. The weight of spent acid was 144 grams or 71.9% recovery.

Example VIII

This example is identical with Example VII except reflux time was increased to 2 hours. 38.4% (of theoretical) of crude trinitrotoluene (92.5% purity) was obtained. The weight of spent acid was 135 grams or 67.6% recovery.

Example IX

This example is identical with Example VII except reflux was increased to 3 hours. The yield of crude trinitrotoluene (88.4% purity) was 38.3 grams or 86.0% of theoretical. The weight of recovered spent acid was 144 g. (71.9%).

Example X

18 grams (0.195 mole) of toluene were added to 200 grams of mixed acid consisting of 30% BF_3 and 70% HNO_3 (98.6%). The experimental procedure was the same as that described in Example I. 36.8 grams (82.7% of theoretical) of crude trinitrotoluene (70.2% purity) was obtained. No separation of liquid phases had occurred between the product and the spent acid using the above mixed acid concentration.

Example XI

This example is identical with Example X except reflux time was increased to 2 hours. The yield of crude trinitrotoluene (85.5% purity) was 38.3 g. (86.0% of theoretical) and no spent acid was recoverable by liquid phase separation.

Example XII

This example is identical with Example X except reflux time was increased to 3 hours. The yield of crude trinitrotoluene (86.6% purity) was 37.8 g. (85.0% of theoretical) and no spent acid was recoverable by liquid phase separation.

Example XIII

A mixture of 200 grams of mixed acid consisting of 60% BF_3 and 40% HNO_3 (98.6%), and 54 grams (0.297 mole) of 2,4-dinitrotoluene (DNT) was refluxed (90°C – 95°C) under constant stirring for a period of two hours. The reaction mixture was cooled to about 70°C , then transferred to a separatory funnel to permit separation of the liquid phases. The top layer, consisting mainly of trinitrotoluene (TNT), was poured into ice water. The product was filtered, washed free of acid and dried. The yield of crude TNT (62.5% purity) was 54.1 grams (80.2% of theoretical). 18 grams (0.195 mole) of toluene was added under vigorous stirring to the recovered spent acid (171 grams) while the temperature of the reaction was maintained between 30°C . to 50°C . After the addition of toluene was completed, the mixture was heated at reflux (90°C – 95°C) for five

minutes, cooled to about 70°C , and then poured into ice water. The solid was filtered, washed free of acid with water, and dried. The weight of crude of crude dinitrotoluene was 21.6 g. (60.7% of theoretical). The lower layer, consisting of spent acid, was 143 grams.

Example XIV

This example is identical with Example XIII except the mixed acid concentration was changed to 50% BF_3 /50% HNO_3 (98.6%). The yield of crude trinitrotoluene (78.0% purity) was 56.3 grams (83.5% of theoretical). 157 grams of recovered spent acid was used to convert 18 grams of toluene to 25.2 grams (70.8% theoretical) of dinitrotoluene. 133 g. of spent acid was recovered.

Example XV

This example is identical with Example XIII except the mixed acid concentration was changed to 40% BF_3 /60% HNO_3 (98.6%). The yield of crude trinitrotoluene (79.5% purity) was 56.1 grams (83.2% of theoretical). 126 grams of recovered spent acid was used to convert 18 grams of toluene to 26.9 grams (75.8% of theoretical) of dinitrotoluene. 99 grams of spent acid was recovered.

Example XVI

This example is identical with Example XIII except the mixed acid concentration was changed to 30% BF_3 /70% HNO_3 (98.6%). The yield of dinitrotoluene (82.0% purity) was 55.2 grams (81.8% of theoretical). 76 grams of recovered spent acid was used to convert 18 grams of toluene to 21.5 grams (60.4% of theoretical) of dinitrotoluene. 40 grams of spent acid was recovered.

Example XVII

This example is identical with Example XIV except the HNO_3 concentration was changed to 95.7%. The yield of crude trinitrotoluene (72.0%) was 54.9 grams (81.5% of theoretical). 157.5 grams of recovered spent acid was used to convert 18 grams of toluene to 23.6 grams (66.5% of theoretical) of dinitrotoluene. 133 grams of spent acid was recovered.

We claim:

1. A process for preparing an explosive selected from the group consisting of 2,4,6-trinitrotoluene and 2,4-dinitrotoluene comprising the steps of reacting toluene with a mixture of boron trifluoride and nitric acid, and refluxing the reacted mixture.
2. The process of claim 1 wherein said explosive consists of 2,4,6-trinitrotoluene and said reacting step comprises reacting toluene with a mixture of about 30 to 60 weight percent BF_3 and the remainder HNO_3 having a concentration of about 98.6%, the molar ratio of said toluene to said HNO_3 ranging from about 1 to 3 to 1 to 10.
3. The process of claim 1 wherein said explosive consists of 2,4,6-trinitrotoluene and said reacting step comprises vigorously stirring at a temperature of about 30 to 50°C . about 18 grams of toluene with about 200 grams of a mixture of 40 to 60 weight percent BF_3 and 60 to 40 weight percent HNO_3 having a concentration of about 98.6%, and wherein the refluxed mixture is cooled to about 70°C , additionally characterized by transferring the cooled refluxed mixture to a separatory funnel and permitting an upper liquid phase and a lower liquid phase to form, pouring said upper liquid phase comprising mainly 2,4,6-trinitrotoluene into ice water to form a product, filtering, washing and drying said product to obtain said 2,4,6-trinitrotoluene.
4. The process of claim 3 further characterized by the steps of pouring said lower liquid phase comprising spent

acid and residual 2,4,6-trinitrotoluene into ice water to form a second product,

filtering, washing and drying said second product to obtain additional 2,4,6-trinitrotoluene.

5. The process of claim 1 wherein said explosive consists of 2,4,6-trinitrotoluene and said reacting step comprises

vigorously stirring at a temperature of about 30 to 50° C. about 18 grams of toluene in about 200 grams of a mixture of 30 weight percent BF_3 and 70 weight percent HNO_3 having a concentration of about 98.6%, and wherein the refluxed mixture is cooled to about 70° C., additionally characterized by pouring the cooled refluxed mixture comprising mainly 2,4,6-trinitrotoluene into ice water to form a product,

filtering, washing and drying said product to obtain said 2,4,6-trinitrotoluene.

6. The process of claim 1 wherein said explosive consists of 2,4-dinitrotoluene and said reacting step comprises vigorously stirring at a temperature of about 30 to 50° C. about 54 grams of 2,4-dinitrotoluene in about 200 grams of a mixture of 30 to 60 weight percent BF_3 and 70 to 40 weight percent HNO_3 having a concentration of about 98.6%,

and said refluxing period is about 60 to 180 minutes, 25 additionally including the steps of

cooling the refluxed mixture to about 70° C.,

transferring the cooled refluxed mixture to a separatory funnel to form an upper liquid phase and a lower liquid phase comprising mainly spent acid,

vigorously stirring about 18 grams of toluene added to

said lower liquid phase while maintaining the temperature at about 30 to 50° C. to form a second mixture,

refluxing said second mixture at about 90 to 95° C. for about 5 minutes,

cooling said refluxed second mixture to about 70° C., transferring said cooled refluxed second mixture into a separatory funnel to form a second upper liquid phase and a second lower liquid phase, said second upper liquid phase comprising mainly 2,4-dinitrotoluene,

pouring said second upper liquid phase into ice water to form a product,

filtering, washing and drying said product to obtain said 2,4-dinitrotoluene.

7. The process as described in claim 6 further characterized by said nitric acid having a concentration of about 95.7%.

8. The process as described in claim 1 wherein the reacted mixture is refluxed at a temperature of about 90-95° C. for a period ranging between about 30 to 240 minutes.
